UNITED STATES PATENT OFFICE.

MICHAEL McCORMICK, OF UNIONTOWN, PENNSYLVANIA.

DAMPER.

No. 828,135.

Specification of Letters Patent.

Patented Aug. 7, 1906.

Application filed April 7, 1905. Serial No. 254,370.

To all whom it may concern:

Be it known that I, MICHAEL McCORMICK, a citizen of the United States of America, residing at Uniontown, in the county of Fayette and State of Pennsylvania, have invented certain new and useful Improvements in Dampers, of which the following is a specification, reference being had therein to the accompanying drawings.

10 This invention relates to certain new and useful improvements in dampers, and more particularly to that type of dampers used in connection with smoke-pipes of coke-ovens.

15 The primary object of this invention is to provide a damper that will withstand the heat to which it is subjected.

Another object of this invention is to provide a damper which will be extremely simple in construction, strong and durable, comparatively inexpensive to manufacture, and highly efficient for the purposes for which it is used.

25 Briefly described, my improved damper consists of a body of fire-clay or the like infusible clay. A metallic strap is employed to bind the body and at the same time provide means whereby it may be manipulated. The damper is particularly adapted to be used in connection with pipes such as used 30 for conveying the products of combustion from coke-ovens to boilers, and the use of the damper in this connection will be hereinafter more fully described.

35 Referring to the drawings accompanying this application, like numerals of reference designate corresponding parts throughout the several views, in which—

40 Figure 1 is a side elevation of a heat-conveying pipe having my improved damper therein. Fig. 2 is a similar view, upon an enlarged scale, of the damper-casing. Fig. 3 is an end view of the same. Fig. 4 is a vertical transverse sectional view of the casing. Fig. 45 5 is a longitudinal sectional view of the casing, illustrating my improved damper mounted therein; and Fig. 6 is a top plan view of the casing.

50 In the accompanying drawings I have illustrated a pipe 1, which establishes communication between a coke-oven 2 and a boiler 3. During the process of manufacturing coke it has been the practice to convey the products of combustion from the coke-ovens to a boiler used for generating steam.

The products of combustion which are conveyed from a coke-oven to a boiler are at a very high heat, and considerable trouble has been experienced in using a damper or valve-gate that would withstand the high degree of temperature to which it was subjected. 55 Metallic dampers or valve-gates have heretofore been used; but in the course of time these dampers or gates warp and succumb to the high degree of temperature to which they are subjected. On account of the damper 60 being first subjected to a high degree of temperature and then removed into an atmosphere of a lower degree of temperature it has warped and rendered it impossible to replace the damper within its casing. To obviate this, I have constructed my improved dampers of fire-clay or the like infusible material. The body portion 4 of the damper in the present instance is entirely constructed of fire-clay; but it is obvious that I may use a 65 clayed body portion consisting of a substantial metallic sheet coated or dressed with an infusible clay.

To handle the body portion of my improved damper and to prevent the edges 70 from being broken or cracked, I surround the same by a metallic strap 5, the ends of which terminate centrally of the top of the body portion and are bent upwardly, as indicated at 6, and secured together by suitable bolts 75 and nuts 7. The bolts serve as means for securing a chain 8 to the damper, whereby it can be easily manipulated.

When the damper is used in connection with a pipe 1, I employ a casing 9, having 80 threaded openings to receive alined sections of pipe, and the casing is formed with an opening 10, within which the damper is adapted to snugly fit.

In Figs. 4 and 5 of the drawings I have 85 illustrated the damper as positioned within this casing, and it will be observed that the metallic strap lies outside of the path of products of combustion conveyed within the pipe 1, consequently being shielded from the 90 heat and not affected thereby.

I do not care to confine the use of my improved damper to pipes employed in connection with coke-ovens, as it is suitable for other purposes than those specified.

105 While I have herein shown the preferred manner of constructing my improved damper, it is obvious that various changes may be

made in the details of construction without departing from the general spirit and scope of the invention.

What I claim, and desire to secure by Letters Patent, is—

A damper comprising a metallic casing having threaded openings in its opposite face walls to receive alined sections of pipe, and having a recess extending into the casing 10 beyond the periphery of said openings and open at the top of the casing, a damper of fire-clay shaped to conform to said recess in the casing and of a size to wholly cover the adjacent ends of the pipe-sections, a metallic binding-strip on the periphery of said dam- 15

per, said binding-strip when the damper is in the casing lying beyond the pipe-opening, the ends of said binding-strip being bent upwardly in parallel relation, a bolt connecting said up-bent ends and binding the strip on 20 the damper, and a second bolt passing through the ends to receive a hoist-chain for lifting the damper, substantially as described.

In testimony whereof I affix my signature in the presence of two witnesses.

MICHAEL McCORMICK.
